LAMP HANGER

Walter B. Engh, Chicago, Ill., assignor to The
Mantle Lamp Company of America, Chicago,
Ill., a corporation of Illinois

Application June 16, 1932, Serial No. 617,569

5 Claims. (Cl. 240—91)

The invention, generically considered, involves a lamp hanger having an eccentrically pivoted lamp-sustaining ring which may be tilted to conveniently receive the bowl of a lamp, and which 5 automatically returns to and remains in its normal horizontal position.

Many old-type hangers have been constructed of such size and design that a solid ring, rigidly supported, is used for the lamp, and the clearance 10 in the hanger between the shade support, or other parts of the hanger, was such that the lamp could be raised above the lamp supporting ring and then lowered and set into the ring. When this is done, however, the hanger is of necessity much 15 longer and undesirable in many ways, and to overcome this a collapsible lamp band support, which could be opened so that the lamp may be inserted from below and the ring then drawn together and locked, with the lamp seated in 20 the ring, has been used.

These collapsible type rings are expensive and not entirely satisfactory, as there is sometimes difficulty in operating the lock.

The hanger disclosed herein is novel in that it 25 includes a solid lamp band ring which is pivoted at two eccentric positions so that it can be tipped to facilitate the entrance of the bowl of the lamp, and which automatically rights itself because of the eccentricity of the pivotal points. This feature makes it very simple to enter or remove a 30 lamp bowl from the ring, and in addition, makes it possible to tip the lamp band 90 degrees or to the same plane as the side rods of the hanger in order to lessen the space required for packing, 35 when the hanger is shipped.

The means of supporting the shade band is also new. The screws which connect the band with the vertical rods of the hanger are longer than necessary, so that the nuts on the end of the 40 screws may be loosened to permit the shade band to be tilted to 90 degrees or to the same plane as the hanger. It is thus possible to ship the hanger with both the lamp band and the shade band in the flat. When in use, however, the shade band 45 is secured in position by tightening the nuts of the retaining screws and is always at right angles to the upright rods. The lamp band, however, can still be tilted whenever it is desired to remove the lamp bowl from or place it within the band.

Referring to the drawing,

Figure 1 shows the hanger in elevation;

Figure 2 shows a side elevation of the hanger, with the lamp-bowl ring and shade-holding band 55 tilted for packing;

Figure 3 is a partial sectional view taken on the line 3—3 of Figure 1;

Figure 4 is a partial sectional view taken on the line 4—4 of Figure 1; and

Figure 5 is a partial view taken on the line 5—5 of Figure 1, the lamp bowl being omitted.

The lamp hanger includes a frame 1 having, at its upper end, supporting means 2 and a pendant bell 3.

The lower ends 1a, 1a of the frame 1 each carry 65 a fixed clip 4 having an upstanding ear 5 which sustains a pivot 6 for the lamp-supporting ring 7, said pivot 6 being eccentrically disposed with reference to said ring 7, so that said ring 7 will be automatically tilted by gravity from an inclined to and remain in its normal horizontal position after a lamp bowl has been placed therein. The body of the clip 4 acts as a stop for said ring 7 when it has moved to either a vertical or 70 a horizontal position.

The shade band 8, on diametrically opposite sides thereof, is provided with recesses 8a which receive the sides of the frame 1, and, extending through said sides and said shade band 8, are screws 9 having nuts 10 of such length that, when 75 said nuts 10 are loosened, said shade band 8 may be tilted to a vertical position.

When the lamp-supporting ring 7 and the shade band 8 are both turned to a vertical position, the parts of the hanger will all be disposed 80 in substantially the same plane, and the hanger will be ready for packing and shipment.

The shade band is provided with the usual shade-supporting elements 11.

Having thus described my invention, what I 90 claim is:

1. A lamp and shade-supporting hanger provided at its lower end with an eccentrically-pivoted lamp-supporting ring and with a stop for said ring when it has turned either to a horizontal or a vertical position, and near its upper end with a shade-supporting band.

2. A lamp and shade-supporting hanger provided at its lower end with an eccentrically-pivoted lamp-supporting ring and with a stop for said ring when it has turned either to a horizontal or a vertical position, and near its upper end with a tilttable shade-supporting band, whereby said hanger may be collapsed for packing.

3. A lamp and shade-supporting hanger provided at its lower ends with fixed stops having ears and a lamp-supporting ring eccentrically pivoted on said ears, and also provided near its upper end with a tilttable shade-supporting band,

110

whereby said hanger may be collapsed for packing.

4. A lamp hanger having a frame, an eccentrically-pivoted lamp-supporting ring disposed at the lower end of said frame, fixed stops for said ring and a shade band, having retractile securing means, carried by the upper end of said frame and adapted to be turned from its normally horizontal to a vertical position.

10 5. A lamp hanger having a frame, a pivoted

lamp-supporting ring, a shade band provided with diametrically-disposed recesses in which the sides of said frame are seated and screws having nuts, extending through said frame and said shade band, said screws being of such length that, when said nuts are retracted, said shade band may be turned from its normal horizontal to a vertical position.
